UNITED STATES PATENT OFFICE.

NORMAN P. HARSHBERGER, OF CHICAGO, ILLINOIS.

ROOFING MATERIAL.

Application filed December 21, 1921. Serial No. 523,838.

To all whom it may concern:

Be it known that I, NORMAN P. HARSHBERGER, a citizen of the United States, residing at Chicago, in the county of Cook and State of Illinois, have invented certain new and useful Improvements in Roofing Materials, of which the following is a specification.

This invention relates to roofing material, and it has for its object the production of suitable shingles or strips of shingling material for covering roofs effectively and so as to give a pleasing appearance.

Of the accompanying drawings Fig. 1 is a perspective view of strips of shingles laid horizontally on a roof, and which embody the features of my invention; Fig. 2 is an enlarged cross-section along the line 2—2 of Fig. 1; Fig. 3 is a view of the lower side 20 of a portion of one of the strips; and Fig. 4 is a diminished plan view of the strips arranged to extend up and down a slanting roof.

Any suitable material may be used for making the strips of roof covering which embody the features of my invention. I prefer for the purpose ordinary sheets of felt, asphalt and slate. Any suitable length or width of strips may be used in carrying out the invention. In covering a roof with ordinary strips of roofing material, if the strips are laid flatly on the roof, overlapping each other more or less, there is a tendency for the strips to bow up or buckle and curl in places, and the appearance of the roof is not pleasing; also the roof is not so well protected where joints are formed. To better protect the roof and improve the appearance, and for other reasons, I provide strips 35 and form transverse folds 6 in the strips, which improve the appearance of the roof and materially assist in preventing buckling and curling tendencies.

The strips may be laid horizontally, as indicated in Fig. 1, or transversely, that is, running down the roof from the peak to the eaves. And the loops may be three-ply as indicated, or may have more folds, if desired.

Where the strips are not of sufficient length to reach from one end of the roof to the other, or from the peak to the eaves, the ends of two strips may be connected in any suitable manner. I prefer for the purpose to make the connection in one of the folds 6 by having the two ends abut and thus form the

center portion 7 of the fold; and I provide an offset portion 8 on each folded strip end, the arrangement being such that the shoulders 9 of the offset portions abut when the two ends are in place. By this arrangement relative longitudinal movement of the strips in one direction is prevented by the abutting ends of the strips and relative transverse movement in one direction is prevented by the abutting shoulders 9; hence, when the strip having the lower end is laid in place, the upper end of the continuation strip is very quickly placed. By this method of joining the ends there is no opportunity for water to leak through as the two ends not only are lapped, but the lower end is turned upwardly and inwardly and, hence, prevents water from working inwardly beyond the end.

Each strip may be lapped onto the lower adjacent strip, as much as may be desired. I prefer to lap them about half way, as is indicated. And in case of the transverse strips running from the peak to the eaves, one strip may lap on both edges of the adjacent strips.

In order to give the folds more strength, or a more pleasing appearance, I provide a filler 12 of some suitable material. These fillers are placed in one of the loops of the folds 6, extending transversely of the strips. These fillers not only increase the thickness of the fold so as to give it a more definite appearance on a roof, but they also stiffen the strips along the folds and thereby prevent the irregular tendencies such as buckling, or warping, or the like. The fillers may be inserted in any suitable manner; I prefer to insert them when the roofing strips are formed, and to have them held securely in place in any suitable manner, as by the adhesive material 13.

As stated, the strips may be laid longitudinally or transversely of the roof as may be desired. In Fig. 4 I have indicated the strips running transversely; and the positioning of the folds in the same strip or in adjacent strips may be as desired. I prefer to lay the strips so that the folds of one strip are staggered with relation to the folds of the adjacent strips. But, while I have illustrated the left-hand edge of the fold 6 in the upper strip abutting against the right-hand edge of the fold in the lower strip, yet it is to be understood that these upper and lower folds may be separated as much as

may be desired, thus varying the appearance of the roof, and otherwise changing the effect.

I claim as my invention:

- 5 1. In a roof covering two strips of sheeting, each of the strips having transverse folds therein, one of the strips being aligned with and being a continuation of the other strip, the adjacent ends of the said two strips abutting together and forming the central portion of a fold, each of said adjacent ends having an offset portion with a shoulder thereon, the shoulders of the offset portions abutting together, thereby preventing 10 relative transverse movement in one direction of said two ends.

- 15 2. An article of manufacture comprising a strip of roofing material having a plurality of transverse folds, and having one end folded to form a fractional portion of one loop of a transverse fold, the said end of the strip having an offset portion between the side edges of the strip.

- 20 3. An article of manufacture comprising a strip of roofing material having one end folded to form a fractional portion of one loop of a transverse fold, and the other end of the strip being similarly folded but on the side of the strip opposite to the fold on the

first mentioned end, each of the edges of the 30 ends comprising two straight portions, not in the same line but parallel with each other.

- 25 4. An article of manufacture comprising a strip of roofing material having a plurality of transverse folds spaced from its ends and having one end folded to form a fractional portion of one of the sides of a transverse fold, and a filler of material running transversely of said strip of roofing material and positioned in each of said folds 40 and in said fractional portion thereof.

- 30 5. An article of manufacture comprising a strip of roofing material having a plurality of transverse folds spaced from its ends and having each end folded to form a 45 fractional portion of one of the sides of a transverse fold, and a filler of material running transversely of said strip of roofing material and positioned in each of said folds 50 spaced from the end and in one of said fractional portions of a loop, and having the facing surfaces of the sides of the fold of the other end of the strip in contact with each other.

In testimony whereof, I hereunto set my 55 hand.

NORMAN P. HARSHBERGER.
